(57) **CLAIM**

The ornamental design for a firearm receiver, as shown and described.

DESCRIPTION

FIG. 1 is a front right isometric view of a firearm receiver according to the present invention.

FIG. 2 is another front right isometric view thereof.

FIG. 3 is a rear left isometric view thereof.

FIG. 4 is a front right bottom isometric view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a bottom view thereof.

The broken lines show a boundary of the claimed invention. The portions of the firearm receiver depicted in de-emphasized half tone in each of the figures are to illustrate environmental structures and any elements shown outside the broken line form no part of the claimed invention.
